PUMP

Mark Henry Kanary, Los Angeles, Calif.

Application October 16, 1939, Serial No. 299,656

4 Claims. (Cl. 103—45)

This invention relates to pumps, and contemplates more specifically apparatus for maintaining pressure on water mains or the like which can be constructed close to the earth and readily adaptable to architectural and garden landscaping.

Devices in popular use for the purpose of the present invention include those which consist generally of tanks mounted upon high towers. Pumps supply water to the tanks which accumulate the power of the pumps in the hydrostatic head of the water in the tanks. While the efficiency of such apparatus is established, the initial cost of construction, combined with their unsightly appearance, renders apparatus of this character unsuitable for many localities.

A general object is to provide in combination two or more master pumps comprising weighted pistons within cylinders communicated with one another through an auxiliary pump which alternately raises said pistons to the top of their stroke, and thereafter permitting their gravitation in response to a balancing of the hydrostatic head in the respective cylinders facilitated by the pumping of water from the cylinder or cylinders in which pistons are being lowered, to the complementary unit or units.

Another object is to provide a plurality of separate pumps associated with each of said master pumps and comprising pistons controlled by the master pistons to maintain pressure of predetermined value on a water main.

Another object is to provide, in combination with pump units of the character above alluded to, pump chambers communicated with the main on which the pressure is to be maintained, having a valve controlled means of communication with the master cylinders, respectively, and into which the pressure in both or either of said cylinders created by the weight of the piston assembly therein may be released, when desired, to thereby meet emergency pressure requirements.

Another object is to provide a releasable connection between the master piston and the separate pistons controlled thereby to enable utilization of a selected number of the separate pistons whereby the capacity of each pump unit directly affecting the pressure in the main may be varied without affecting the speed of piston reciproca-

tion.

Other objects and corresponding advantages such, for example, as facility of control, simplicity in construction, and economy of manufacture due to the fact that most of the principal parts of the apparatus may be constructed of pipe of

stock sizes, will be apparent to those of skill in the art from an examination of the following description read in the light of the accompanying drawing, in which:

- 5 Fig. 1 is a sectional view, partially in elevation, illustrating one form of my invention embodying two pump units;
 Fig. 2 is a sectional view taken on lines 2—2 of Fig. 1;
 10 Fig. 3 is an enlarged sectional view of the lower end of one of the smaller pumps of which there are several in each unit, illustrating particularly the means for releasably securing the piston thereof in the lower end of its cylinder when not in use.

Referring to the drawing in detail, the numerals of which indicate similar parts throughout the several views, 5 designates a cement foundation by which spaced water tanks 6 and 7 are supported. Between adjacent end walls 8—8 of tanks 6 and 7, a common inlet chamber 9 is formed. The tanks 6 and 7 and the inlet chamber 9 are closed by the floor 10 of a pair of pump units A and B about to be described. Tanks 6 and 7 are communicated with the reservoir (not shown) by a pipe 11 leading into inlet chamber 9 through an opening 12 in floor 10 between the pump units. An inlet port 13 in each end wall 8 is controlled by a separate check valve 14 hinged within respective tanks 6 and 7 to admit water from inlet chamber 9, but adapted to close to a balance of pressure within the tanks. Pipes 15 leading from the opposite ends of tanks 6 and 7, respectively, communicate with the water main (not shown) to direct water under pressure within the tanks to the main. Check valves 16 are pivoted to the ends of the tanks in respective pipes 15 for controlling the flow of water between tanks 6 and 7 and main, said valves being adapted to close to pressure in pipes 15.

Pump units A and B are mounted on floor 10 over tanks 6 and 7, respectively, with which they are adapted to cooperate to draw water from the reservoir through pipe 11 and expel the same under predetermined pressure through pipes 15. The pump units A and B are identical and accordingly, it will be understood that the following specific description of one of them is a description of either.

50 Centrally located over each tank on floor 10 is a large master cylinder 17. A plurality of pump cylinders 18 of smaller cross-section are arranged in equi-spaced relation around master cylinder 17 on floor 10. Each pump cylinder 18 is in unrestricted communication with tank 6

or 7 of the respective pump units through an opening 19 in the floor (see unit B). The upper ends of each pump cylinder 18 and the master cylinder 17 are connected to the underside of a reinforcing roof 20 which maintains the position of the various cylinders 17 and 18. A master piston 21 comprising a pipe section is reciprocably disposed in cylinder 17, and extends upwardly through an opening in the reinforcing roof 20. A packer 22 of leather or other suitable material, is clamped between the lower end of the piston 21 and a supporting member 23 therefor. (See pump unit A.) The upper end of the master piston is secured to the underside of a horizontal platform 24 which extends laterally so as to overhang the pump cylinders 18. 25 indicates a plurality of weights mounted on top of platform 24 to assist the gravitation of the platform and piston 21. A series of cylindrical hubs 26 are secured to the underside of platform 24 in concentric alignment with respective pump cylinders 18. A pump piston 27 is adapted to reciprocate within each cylinder 18 and comprises a section of pipe protruding from within its respective cylinder through an opening in the roof 20 for releasable attachment of its upper end to the respective hub 26 aligned therewith into which it extends. One or more pins 28 mounted on the upper end of each piston 27 extend into inverted L-shaped slots 29 formed in the lower edge of the hub 26 with which the respective piston cooperates to lock the pistons to the platform 20.

The bore of each piston 27 is closed by a plug 30 (Fig. 3) threaded into the lower end thereof. A packer 31 is secured to each plug 30 to engage the bore of the respective cylinders. Each packer 31 is reinforced by a plate 32 connected to the piston by a nut 33. A piston retainer 34, comprising a short section of pipe, is secured by suitable means to the underside of plate 32 in coaxial alignment with the piston 27. Each retainer is formed with one or more inverted L-shaped slots 35 opening through the lower edge thereof. Transverse pins 36 mounted in the bore of the cylinder on radii thereof are spaced apart distances corresponding to the spacing of the slots 35 in retainer 4. The pistons 27 may thus be disengaged from the hubs 26, secured to the platform, by moving the pins 28 out of the slots 29, and locked immovably in the cylinders 17 by rotating the pistons to bring the slots 35 of the retainer into registry with pins 36.

Apart from the pump units, I provide a control pump 37 of standard design and manufacture, from which a pipe 38 leads into the bottom of the cylinders of pump unit A. A T-fitting 39, forming a part of pipe 38, provides a means of connection for a branch pipe 40 which communicates pipe 38 with the master cylinder 17 of pump unit B. Another pair of pipes 41 and 42 lead from the bottom of the cylinders 17 of the respective pump units to a cross fitting 43 which is connected to the inlet side of pump 37 by conduit 44. Arranged in each of the four pipes 38, 40, 41, and 42, adjacent the master cylinders with which they communicate, is a mechanically operated valve bearing numerals 45, 46, 47, and 48, in the respective pipes, as illustrated. As the particular construction of these valves does not form a part of the present invention, they are not specifically described or illustrated. A water supply tank 49 is communicated with the inlet end of pump 37 through a conduit 50 connected to cross fitting 43. A valve in the conduit, generally 75

designated by the numeral 51, is normally closed, being opened only when it is desirous of admitting water into the pipes 38, 40, 41, and 42, and master cylinders 17. The supply tank 49 is filled through a valve-controlled inlet tube 52 connected to a source of supply (not shown).

Tanks 6 and 7 will be filled by the pressure of water flowing from the reservoir through pipe 11 or water may be initially drawn into the tanks by the pumps 37, as about to be described. Normal operation of the apparatus is begun by energizing pump 37 after first opening valve 51 to communicate supply tank 49 and the pump through conduits 50 and 44. As above noted, the flow of water through pipes 38, 40, 41 and 42, respectively, is controlled by the valves 45-48, the operation of which is synchronized by auxiliary mechanism (not shown) of any of various well known types. When the pump is started, valve 45 of pipe 38 is open and all other valves 46, 47, and 48 are closed. Water will, accordingly, be drawn from supply tank 49 and pumped into the master cylinder 17 of pump unit A through pipe 38, so as to raise the master piston 21, the weight 25, and each of the pistons 27 which are connected to said master piston. The upward movement of the pistons 27 of unit A draws water from the inlet chamber 9 and pipe 11 through the check valve 14 to fill the tank 6 or, if the tank has theretofore been filled by fluid from the reservoir, additional water will be drawn in to fill the cylinders 18. Valve 45 in pipe 38 is then closed and the valves 46 and 47 in pipes 40 and 41 opened. The operation of pump 37 may be continuous. The water within cylinders 17 of pump unit A will, accordingly, flow into pipe 41 and thence into pump 37 and pipe 40 to the master cylinder 17 of pump unit B. The weight of the water in cylinder 17 of the first unit will thus assist the elevation of the piston of the second unit until the water in cylinders 17 of both units reaches a common level, after which pump 37 continues to draw water from the cylinder of the first unit, permitting piston 21 therein to gravitate while simultaneously raising the correspondingly numbered piston of the second unit. Water will be drawn by pump 37 from supply tank 49 in an amount sufficient to fill one of the cylinders and the various pipes which connect the cylinders with the pump, whereupon valve 51 is closed. Accordingly, when the piston 21 of the pump unit B reaches the top of its stroke, all water will have been removed from the cylinder 17 of pump unit A. Valves 46 and 47 are then closed and valves 45 and 48 opened, whereupon the pump will draw the water into pipe 42 and transfer the same through pipe 38 into the cylinder 17 of the unit A to raise the piston 21 therein, as well as pistons 27 associated therewith. The pair of valves 45 and 48, and the pair 46 and 47 are opened and closed alternately as one or the other of the pistons 21 reaches the top of its stroke. As the platforms 24 are raised on each alternate stroke of the respective pistons 21, pistons 27 will be raised to draw water into the tanks from pipe 11 through the inlet chamber 9. On the opposite stroke of the pistons 27 of the respective units A and B, the volume of water drawn into the tanks on the preceding stroke of said pistons will be expelled through pipes 15 into the main to maintain the desired pressure therein.

An opening 53 in the floor 10 of each master cylinder 17 is provided to communicate respec-

tive cylinders and water tanks 6 and 7. Slide dump valves 54 normally close the openings 53, and during the operation above described, remain in closed position. Screws 55, threaded through bosses 56 on the underside of the valves 54, control the position of said valves by their rotation in an obvious manner. Should additional pressure be needed on the main, the valves 54 may be opened by rotation of the screw 55, and the full weight of the platform, weights, and all pistons will be exerted downwardly to displace the water in cylinders 17 and 18 of both units A and B. Valves 54 or either of them may be opened regardless of the position of pistons 21 in the master cylinders 17, thus providing means to meet pressure requirements at any time and on a moment's notice.

The number of pistons 21 employed determine the capacity of the pump units A and B, which may be varied by disengaging certain of the pistons 21 from their hubs 26. The pistons not used may be locked in the lower end of their respective cylinders 18 by means of pins 36 to obviate their tendency to float, as water is raised in the cylinders 18 in which pistons 21 are reciprocated.

It will be observed that the respective pump units A and B balance one another and when raised each will gravitate to the middle of its stroke without the aid of pump 37, and accordingly, the only pressure required to be produced by pump 37 will be that necessary to raise each piston 21 half of its stroke, while the pistons 21 are effective throughout the entire stroke of the respective pistons 21 to pump fluid from the reservoir to the main through tanks 6 and 7.

While I have illustrated and described but one embodiment of my invention, it will be understood that the specific arrangement, as well as size, shape, and proportion, of the various parts of the pump units may be varied; that additional pump units may be utilized, thus increasing, in proportion to the number of additional units, the capacity of the entire pump assembly; that the means for connecting the pistons 21 to platform and for locking them in their respective cylinders, is merely illustrative, and susceptible of substitution by other means well known in the art—all without departing from the spirit of my invention as defined by the appended claims.

What I claim and desire to secure by Letters Patent is:

1. In a device of the character described, a pair of master cylinders, a master piston in each of said cylinders, a plurality of pump cylinders associated with each master cylinder, a pump piston in each of said pump cylinders releasable, means connecting said pump pistons with respective

master pistons so as to move therewith, means to releasably connect said pump pistons immovable relative to their cylinders when said pump pistons are released from said first-named means to prevent movement of the pump pistons during reciprocation of said master pistons, an auxiliary pump, valve-controlled conduit means to communicate the outlet end of said auxiliary pump with either of said master cylinders, and valve-controlled conduit means to selectively communicate said master cylinders with the inlet end of the auxiliary pump.

2. In a device of the character described, a pump unit comprising a tank, inlet and outlet conduits connected to said tank, a series of pumps superposed with relation to said tank and comprising cylinders communicated with said tank, a pump piston in each of said cylinders, a motor associated with said first-named series of pumps and comprising a master piston connected to said pump pistons of the first-named series of pumps, means to supply fluid to said motor, means to actuate said motor to energize said series of pumps and thereby move fluid from said inlet conduit into said tank and through said outlet conduit, and a valve controlled means to communicate said motor with the tank to release the fluid in said master cylinder into the tank.

3. In a device of the character described, a pair of pump units each comprising a tank, a series of pumps superposed with relation to each of said tanks, each of said pumps comprising a cylinder communicated with the tank over which it is disposed, a pump piston in each of said cylinders, a motor in each pump unit comprising an axially vertical master cylinder, and a master piston in each of said last-named cylinders, connected to the pump pistons of its respective pump unit, means to actuate said motors comprising a means of communication between the master cylinders to direct the flow of liquid in one thereof to the other, each of said master cylinders having a means of communication with the tanks of the respective pump units of which said cylinders are a part to release the fluid in said master cylinders into the tanks, respectively.

4. In a device of the character described, a motor comprising a master cylinder and a master piston in said cylinder, and a series of pumps associated with said master cylinder and piston, each of said pumps comprising a cylinder and piston, means to releasably connect said last-named pistons to said master piston, and releasable means to secure the pistons of each of said pumps against longitudinal movement in its respective cylinder when disconnected from said master piston.

MARK HENRY KANARY.
